UNITED STATES PATENT OFFICE.

WOLCOTT A. HULL, OF NEW YORK, N. Y., ASSIGNOR OF ONE-HALF TO THE ANSONIA BRASS AND COPPER COMPANY, OF SAME PLACE.

SUSPENSION-LAMP.

SPECIFICATION forming part of Letters Patent No. 367,144, dated July 26, 1887.

Application filed February 6, 1884. Serial No. 119,899. (No model.)

To all whom it may concern:

Be it known that I, WOLCOTT A. HULL, of New York, in the county of New York and State of New York, have invented a certain 5 new and useful Improvement in Lamps, of which the following is a specification.

I will describe my improvement in connection with a lamp embodying it, and then point out the various features in claims.

10 In the accompanying drawings, Figure 1 is a side view of a lamp-fixture embodying my improvement. Fig. 2 is a transverse section of the shade-holder and a sectional view of a hook with which it is provided. Fig. 3 is a 15 transverse section of one of a number of rods whereby the shade-holder is suspended. Fig. 4 is a longitudinal section of the end portion of one of these rods. Fig. 5 is a transverse section of a connecting-piece whereby certain 20 of the suspending-rods are united, and Fig. 6 is a perspective view of a shade-crown.

Similar letters of reference designate corresponding parts in all the figures.

A designates a lamp-reservoir holder. It 25 may be of any suitable construction. Its construction forms no feature of my present invention.

B designates a shade-holder consisting of a sheet-metal ring provided at the lower edge 30 with an inwardly-turned flange, b.

C designates arms, which may be of any suitable construction and extend between the reservoir-holder A and the shade-holder B. They are fastened by screws to both the reservoir-holder and the shade-holder. Their construction 35 is not involved in this improvement.

On the exterior of the shade-holder are hooks D. They are made of thick metal, preferably brass, and may be cast or struck up. Their 40 shanks fit snugly against and are arranged approximately parallel with the exterior of the shade-holder, and are provided at the lower ends with offsets d at approximate right angles to the shanks, which extend under the inwardly-turned flange b of the shade-holder. These offsets d are fastened by screws, rivets, or other means to the flange b. The shanks 45 of the hooks are wide, so as to have an extensive bearing on the exterior of the shade-holder, and hence distribute over a large surface any force that may be exerted by them to

the shade-holder. The hooks extend outwardly from the shanks, and, as the means whereby the shade-holder is suspended will converge upwardly, the tendency will be to 55 force the shanks of the hooks against the exterior of the shade-holder. Owing to this the shanks of the hooks do not need to be fastened to the exterior of the shade-holder, and the fastening of their offsets d to the flange b will 60 suffice.

I have shown the shade-holder as provided with outwardly-projecting ornamentation—in this instance, corrugations—and the upwardly-extending portions of the hooks D bearing 65 against such ornamentation. The ornamentation tends to prevent the crushing in of the shade-holder by the hooks, and enables the use of thinner metal than might otherwise be used in the manufacture of the shade-holder. 70

With the hooks D engage hooks e at the ends of rods E. These rods E at the upper ends have hooks or loops e', that engage with a connecting-piece, F. Rods G extend from the connecting-pieces F to chains H, that pass 75 around pulleys in a hanger, I, and are connected to a weight, J. The rods G have at their lower ends hooks g, which engage with the connecting-pieces F, and at their upper ends hooks g', which engage with the chains H. 80

The rods E G are made externally of spiral form. The rods E converge in pairs to one of the connecting-pieces F, and from each connecting-piece a single rod, G, extends. The rods G may be stouter and stronger, if desirable, because they have to sustain the weight which is borne by the pairs of rods E with which they are united by the connecting-pieces. The spiral exterior of the rods imparts an ornamental appearance to them, and, 85 moreover, materially stiffens them, so as to reduce their liability of being bent.

The hooks of the rods E G are made separately from them.

The connecting-pieces F are shown as severally made of a sheet-metal plate having the central portion embossed to ornament and stiffen it against bending, and the edge portion scalloped. The hooks e' of the rods E and the hooks g' of the rods G engage with holes 90 arranged in the edge portion of the plates which form the connecting-pieces F. The

weight J is guided by a rod, K, depending from the hanger. A smoke-bell, L, hangs from the lower end of the rod K.

M designates a shade-crown adapted to fit 5 upon the upper part of the shade N. It is preferably made of sheet metal. Internally it is provided with resilient fingers f, made of sheet metal and riveted at one end only to the crown. These fingers center the shade-crown 10 and exert only a resilient pressure upon it.

What I claim as my invention, and desire to secure by Letters Patent, is—

1. The combination, with a shade-holder consisting of a sheet-metal ring and provided 15 with outwardly-projecting ornamentation and

an inwardly-turned flange at its lower edge, of hooks extending outwardly from shanks, arranged approximately parallel with and bearing against the ornamentation on the shade-holder, and provided with offsets at approximate right angles to the shanks, extending under the flange of the shade-holder and fastened thereto, substantially as specified. 20

2. A shade-crown provided internally with resilient fingers, substantially as specified.

WOLCOTT A. HULL.
